PRISMATIC PENDANT FOR A LAMP OR
SIMILAR ARTICLE

Abraham L. Buschman, New York, N. Y.

Application March 2, 1955, Serial No. 34,820

Term of patent 7 years

(Cl. D48—3)

Fig. 1 is a front view of a prismatic pendant for a lamp or similar article showing my new design;

Figs. 2 and 3 are side and rear views, respectively, of said pendant; and

Fig. 4 is a sectional view taken substantially along the line 4—4 of Fig. 3.

I claim:

The ornamental design for a prismatic pendant for a lamp or similar article, substantially as shown.
